(57) **CLAIM**

We claim the ornamental design for a bottle, as shown and described.

DESCRIPTION

FIG. 1 is a perspective view of a bottle, showing a first embodiment in accordance with our new design;
 FIG. 2 is a first side elevational view thereof;
 FIG. 3 is a second side elevational view thereof;
 FIG. 4 is a front elevational view thereof;
 FIG. 5 is a back elevational view thereof;
 FIG. 6 is a top view thereof;
 FIG. 7 is a bottom view thereof;
 FIG. 8 is a perspective view of a bottle, showing a second embodiment in accordance with our new design;
 FIG. 9 is a first side elevational view thereof;
 FIG. 10 is a second side elevational view thereof;
 FIG. 11 is a front elevational view thereof;
 FIG. 12 is a back elevational view thereof;
 FIG. 13 is a top view thereof; and,
 FIG. 14 is a bottom view thereof.

The dash-dash broken lines shown illustrate portions of the bottle that form no part of the claimed design.

1 Claim, 8 Drawing Sheets(56)
